[57] CLAIM

The ornamental design for a magnetic resonance imaging apparatus, as shown and described.

DESCRIPTION

FIG. 1 is a perspective view looking from the front of the magnetic resonance imaging apparatus showing our new design;

FIG. 2 is a front elevational view, the rear elevational view, right side elevational view and left side elevational views being identical to the front elevational view; and, FIG. 3 is a top plan view taken in the direction of line 3—3 of FIG. 2.

Broken line detail is provided in the figures to show the environment in which the claimed design is associated and is itself not part of the claimed design.
